Attorney

UNITED STATES PATENT OFFICE.

ALLEN GLENN FLORY, OF WINCHESTER, IDAHO.

GATE.

1,224,087.

Specification of Letters Patent. Patented Apr. 24, 1917.

Application filed December 22, 1916. Serial No. 138,426.

To all whom it may concern:

Be it known that I, ALLEN GLENN FLORY, a citizen of the United States, residing at Winchester, in the county of Lewis and 5 State of Idaho, have invented new and useful Improvements in Gates, of which the following is a specification.

This invention relates to gates, and it has for its object to produce a gate of simple and 10 improved construction which may be easily and expeditiously lifted and sustained at various elevations, enabling the gate to clear obstructions, such as snow drifts and the like, which would interfere with the operation 15 thereof if permitted to remain in normal position.

A further object of the invention is to simplify and improve the construction and operation of the parts whereby the gate is 20 swingingly supported, enabling the gate to be adjusted to and supported at various elevations without interfering with the swinging movement thereof.

With these and other ends in view which 25 will readily appear as the nature of the invention is better understood, the same consists in the improved construction and novel arrangement and combination of parts which will be hereinafter fully described 30 and particularly pointed out in the claim.

In the accompanying drawing has been 35 illustrated a simple and preferred form of the invention, it being, however, understood that no limitation is necessarily made to the precise structural details therein exhibited, but that changes, alterations and modifications 40 within the scope of the claim may be resorted to when desired.

In the drawing,—

45 Figure 1 is a view in side elevation of a gate constructed in accordance with the invention.

Fig. 2 is a vertical sectional view of the 50 adjusting device.

Fig. 3 is an elevation illustrating a modification.

Fig. 4 is a sectional detail view taken on the line 4—4 in Fig. 3.

55 Corresponding parts in the several figures are denoted by like characters of reference.

The gate post 15 is provided with supporting means, such as eye bolts 16, in which a rod or pipe 17 is supported in any convenient manner, such as by keys or set screws 18. The gate G which may be of any desired construction and which may be made

of any desired material or combination of materials is equipped with strap hinges 19 engaging the rod or pipe 17, which latter may be designated as the hinge rod. The 60 gate is equipped with a latch member 20 adapted for locking engagement with a vertical notch or slot 21 in the latch post 22, said notch or slot being of such extent as to be capable of being engaged by the latch 65 member in any position to which the gate may be vertically adjusted. A brace member 23 extends from the latch end of the gate to the hinge rod 17, said brace member being provided with a sleeve 24 engaging 70 said rod. The eye bolts 16, the hinge straps 19 and the sleeve 24 must be relatively so arranged as to permit the requisite vertical movement of the gate with respect to the hinge rod. 75

An adjusting member or jack member, generally designated by H, is provided, the same comprising a sleeve 25 engaging the hinge rod 17 on which it is fitted for rotation by means of set collars 26. The sleeve 25 is 80 provided with laterally extending arms 27 between which is journaled a pinion 28 and a spur wheel 29 meshing therewith, the shaft 30 that carries the pinion 28 being provided with a crank 31, whereby it may be rotated. 85 The spur wheel 29 is engaged by a spring actuated dog 32, whereby it is normally held against rotation. Fixed on the end of the gate, in mesh with the spur wheel 29, is a rack bar 33, said rack bar and the rear portion 90 of the gate being guided between the arms 27 of the jack, so that when the gate is swung about the axis of the hinge rod 17, a correspondingly swinging movement will be imparted to the jack member. 95

It will be seen that by disengaging the spring actuated dog 32 from the spur wheel 29 and rotating the latter through the medium of the crank shaft carrying the pinion 28, the gate may be vertically adjusted so as 100 to enable it to clear snow drifts and other obstructions, the hinge straps 19 and the sleeve 24 sliding along the hinge rod 17, while the jack member is prevented from sliding by the set collars 26. When the obstruction is removed the gate may be again lowered as will be readily understood. The gate may also be raised and sustained at a distance above the ground which will permit small stock, such as pigs, to pass beneath the 110 gate, while other animals, such as horses and cattle, are prevented from passing, the ad-

vantage of such adjustment being readily apparent.

By the modified construction of this device illustrated in Figs. 3 and 4, the shaft 34 carrying the spur wheel 29 is extended beyond the outer side face of one of the arms 27, said shaft being equipped with a drum 35. A flexible hoisting element, such as a slender cable 36, is provided, said hoisting element being terminally connected at one end with the drum 35 and at the other end with the gate, and said hoisting element being guided over guiding means, such as pulleys 37, at the top of the gate post. By this construction the rack bar 33 is dispensed with, and it will be seen that by rotation of the crank 30 the hoisting element may be wound upon or unwound from the drum 35, thereby raising or lowering the gate which will be retained at the desired elevation for engagement of the dog 32 with the spur wheel 29.

As will be seen from the foregoing description, taken in connection with the drawing hereto annexed, I have produced a gate ²⁵ which is simple in construction and which will be found to be thoroughly efficient for the purposes for which it is provided.

Having thus described the invention, what is claimed as new, is:—

A gate post, a hinge rod supported thereby, a gate having hinge members engaging the hinge rod, a jack member including a sleeve fitted for rotation on the hinge rod and having laterally extending arms, shafts ³⁵ supported by said arms, one of said shafts having a crank and a pinion, and the other shaft carrying a spur wheel in mesh with said pinion, and a spring actuated dog engaging the spur wheel; in combination with ⁴⁰ hoisting means actuated by the crank.

In testimony whereof I affix my signature.

ALLEN GLENN FLORY.
